UNITED STATES PATENT OFFICE.

WILLIAM H. BAKER, OF BOSTON, MASSACHUSETTS, ASSIGNOR, BY MESNE ASSIGNMENTS, TO DRAPER CORPORATION, OF HOPEDALE, MASSACHUSETTS, A CORPORATION OF MAINE.

FILLING-REPLENISHING LOOM.

1,242,098.

Specification of Letters Patent.

Patented Oct. 2, 1917.

Application filed June 31, 1915. Serial No. 35,234.

To all whom it may concern:

Be it known that I, WILLIAM H. BAKER, a citizen of the United States, residing at Boston, county of Suffolk, and State of Massachusetts, have invented an Improvement 5 in Filling-Replenishing Looms, of which the following description, in connection with the accompanying drawings, is a specification, like characters on the drawings representing like parts.

The invention to be hereinafter described relates to filling replenishing looms, wherein the filling carrier is automatically changed at or prior to complete exhaustion of the 15 filling; or upon breakage thereof; and more particularly, it has reference to such filling replenishing looms of the "overpick" type.

In looms of the "overpick" type, the shuttle is thrown across the lay by means 20 of a picker which travels on a guide rod or spindle. This guide rod or spindle is usually positioned above the shuttle-box and the picker extends therefrom down into the path of the shuttle. The position of the 25 guide rod or spindle is such that it seriously interferes with the filling replenishing mechanism and its adjuncts as now commonly found on filling replenishing looms.

With these generally-stated facts in mind, 30 the present invention contemplates the provision of means whereby the shuttle-box or shuttle of an "overpick" loom may be provided at desired times with a fresh supply of filling.

35 An important feature of the present invention consists in mounting the shuttle-box and guide rod or spindle at the filling replenishing side of the loom in such manner that upon call for filling replenishment, 40 they shall be moved relatively into a position to permit the filling replenishing mechanism to perform its intended function.

Another important feature of the invention 45 consists in the means employed for preventing actuation of the filling replenishing mechanism when the shuttle is not properly positioned in the box at the filling replenishing side of the loom at the time said box and guide rod or spindle are moved 50 relatively to position the parts for change of filling.

A still further feature of the present invention consists in means for holding the shuttle in fixed position in its shuttle-box at

the filling replenishing side of the loom during change of filling.

Another important feature of the present invention consists in the filling carrier supplying means, whereby a filling carrier is placed in position for the action of the replenishing mechanism.

It is an object of the present invention, also, to so construct and simplify the combination and arrangement of parts as to enable "overpick" looms now in use to be provided with the present invention without material alteration in the general construction thereof, all of which will be best understood from the following description and accompanying drawings of one form of 65 means for carrying the present invention into practical effect.

While the present invention in its various features is hereinafter described in connection with an "overpick" loom, wherein they 75 have special adaptation, it is to be understood that many of these features may be employed in looms of other types, without departing from the true scope of the actual invention.

In the drawings:—

Figure 1 is a side elevation of an "overpick" loom at the filling replenishing side, showing the present invention applied thereto;

Fig. 2 is an enlarged side elevation of the upper portion of the loom at the filling replenishing side, showing the various features of the invention in the position they assume during normal operation of the 90 loom;

Fig. 3 is a view similar to that of Fig. 2, showing the position the parts assume upon call for filling replenishment, and also the position of the filling replenishing mechanism as it transfers a filling carrier from the hopper to the shuttle-box;

Fig. 4 is a front elevation at one side of the loom showing the filling replenishing mechanism and features of the present invention, some of the parts being broken away;

Fig. 5 is a plan view of the same side of the loom; and

Fig. 6 is a detail enlarged view partly in section, showing a filling carrier in the hopper and another in position ready for transfer.

The loom frame 1 may be of any usual and appropriate character for supporting the operating parts, and in the present form of the invention is shown as comprising suitable side frames with connecting braces. Mounted in suitable bearings 2 of the loom frame, Fig. 1, is the crank shaft 3 to which is connected the pitman 4 jointed at 5 to the lay 6. The lay is supported by the usual swords 7 mounted to rock in suitable bearings 8 on the lower portion of the loom frame. Mounted in suitable bearings 9 secured to the loom frame is the pick shaft 10 having adjustably secured at its upper end, the picker arm 11 to which is connected the strap 12, as usual.

Secured to the lay 6 in any appropriate manner, is the picker guide rod or spindle 13 on which is mounted to slide, the picker 14 appropriately connected to the picker strap 12, the construction of parts being such that the picker 14 may freely slide upon the guide rod or spindle 13 under the impulse of the picker strap 12 to impart to the shuttle its picking motion and to be moved by the shuttle toward the outer end of the shuttle-box as the shuttle returns thereto. The parts so far described may be of usual construction, as found in "overpick" looms, and being well understood in the art, further elucidation of these matters will be unnecessary.

As hereinbefore noted, the guide rod or spindle on which the picker slides, in this type of loom, is usually positioned with respect to the shuttle-box to interfere with the action of the filling replenishing mechanism. In the present illustrated form of "overpick" loom, the spindle is indicated as positioned above or over the shuttle-box, and obviously, entrance of a filling carrier into the shuttle-box from above is precluded by the position of the spindle relatively thereto. The present form of the invention, therefore, contemplates moving the shuttle-box at the filling replenishing side of the loom to one side of the lay or picker spindle, in order to permit a filling carrier to be transferred from above to the shuttle-box. In the present form of the invention, also, the filling carriers are indicated as being of the bobbin form with appropriate amounts of filling wound thereon.

In carrying this feature of the present invention into practical effect, the shuttle-box at the filling replenishing side of the loom is mounted for movement with the lay, and also for movement relatively thereto under call for filling replenishment; and a practical means for carrying this feature of the invention into effect will now be described.

Mounted for rocking movement upon the lay sword 7, at the filling replenishing side of the loom, as at 15, Fig. 1, is an upright

or arm 16 which, at its upper portion, has the two parts 17 and 18, Fig. 4, which parts are separated an appropriate distance for the passage of a filling carrier or bobbin from the shuttle as will be readily understood.

Mounted upon the portions 17 and 18 of the arm 16, Fig. 3, is the shuttle-box for receiving the shuttle at the filling replenishing side of the loom, and holding it for operation of the transferring mechanism. This shuttle-box in the present form of the invention, comprises the base portion 19, Fig. 3, having the front wall 20 and the rear binder 21 between which the shuttle 22 is adapted to be received as usual. In order to bring the top surface of the base portion 19 of the shuttle-box into the line of the race, the lay, at the filling replenishing side, is suitably cut away as at 23 to receive the base portion 19 of the shuttle-box and is likewise suitably provided with a guide portion 24 to direct the discharged carrier as it passes out of the shuttle-box. The shuttle-box itself, as well as the shuttle, may have the usual lower openings for the passage of the discharged filling carrier, but since these are well understood by those skilled in the art, their detail illustration herein is not regarded as necessary.

Secured to the lay 6 opposite the portions 17 and 18 of the shuttle-box carrying frame, are suitable brackets 25 to each of which is pivotally mounted, as at 26, one arm 27 of a toggle, the other arm 28 of which is pivoted at 29 to a suitable bracket 30 secured to each of the arms 17 and 18 of the shuttle-box carrying frame. The pivotal mounting for the toggles 27 and 28, as at 26, preferably is in the form of a rock shaft, 105 as indicated in Fig. 4, and extending from the rock shaft toward the rear of the loom is the arm 31, and to the end of said arm 31 is connected one end of a spring 32, the other end of said spring being connected to the lay sword 7, preferably at the pivotal mounting of the shuttle frame supporting rod 16, Fig. 1, the construction being such that the spring 32 normally acting upon the toggles 27 and 28 serves to maintain them 115 "broken", or in the position indicated by Figs. 1 and 2.

When the toggles 27 and 28 are "broken" under the action of the spring 32, the shuttle-box at the filling replenishing side of the loom is held in normal or weaving position with the shuttle-box substantially under or below the picker spindle or guide rod 13. With the shuttle-box in this position with relation to the picker spindle or guide rod 13, it is evident that difficulty would be encountered in transferring a filling carrier from the hopper to the shuttle-box, and in order to overcome this difficulty, means are provided which, upon call for filling re- 130

plenishment, move the shuttle-box at the filling replenishing side of the loom to one side of the lay, preferably toward the front, to place the shuttle-box in position for the transfer thereto of a fresh filling carrier.

Mounted upon the front portion of the loom frame is the transverse or change shaft 33, Figs. 2 and 3, which, as usual in filling replenishing looms, is given a rocking movement when the filling is to be changed. This rocking movement may be effected either through the usual feeler mechanism prior to complete exhaustion of the filling in the shuttle, or it may be effected by detecting mechanism such as a filling fork, when the filling breaks or becomes completely exhausted. Both these mechanisms, however, for rocking the transverse or change shaft, are well known and understood by those skilled in the art, and as their particular constructions form no essential part of the present invention, it is not necessary further to describe the same.

Secured to the rock shaft 33 is a sleeve 34 having projecting therefrom, the lifter arm 35, the lower hooked end 36 of which is positioned below the dagger 37 which is itself pivoted at 38 to an arm 39 extending downward from the shaft 26 to which the toggle members 27 and 28 are secured. Mounted in a suitable bracket 40 secured to the loom frame, as indicated in Figs. 1 and 3, is a bunter for engaging the dagger 37 when the end of said dagger is raised into the position indicated in Fig. 3. In the present form of the invention, the bunter comprises a threaded rod 41 adjustably mounted in the lug 42 of the bracket 40 and secured in position by the nuts 43. The threaded rod 41 is thus adjustable in the lug 42 and carries a bunter head 44 which is preferably hollowed out or formed with a contacting seat for engagement by the dagger 37 when the lay beats up after a call for filling replenishment. A spring 45 having one end connected to the pin 46 of the arm 31 and the other secured to a projecting lug 47 from the dagger 37, serves to normally hold the dagger 37 with its bunter contacting end depressed into the position indicated in Figs. 1 and 2; but upon call for filling replenishment, it yields to permit the dagger 37 to be raised by the arm 35 into position to contact with the bunter 44, as indicated in Fig. 3.

From the construction thus far described with respect to the shuttle-box at the filling replenishing side of the loom, it will be noted that the shuttle-box is normally maintained in position at the end of the lay below the picker guide rod 13 by means of the spring 32 and that the toggle 27, 28 is normally "broken." On call for filling replenishment, however, the transverse or change shaft 33 is rocked by either the feeler or de-

tecting mechanism and the end of the dagger 37 is raised into position to contact with the bunter head 44 so that as the lay beats up, the dagger 37 strikes the bunter head and straightens the toggle 27 against the tension of its spring 32, thereby moving the shuttle-box carrying frame and shuttle-box toward the front of the lay into position for the action of the transferring mechanism. After the transfer, as will hereinafter more fully appear, the lay moves backward, the transverse or change shaft 33 returns to its initial position, the dagger 37 likewise returns to initial position, and the toggles 27, 28 are "broken" by the spring 32, thereby returning the shuttle-box at the filling replenishing side of the loom to its normal or weaving position, as indicated in Fig. 2.

In the present form of the invention, the shuttle-box at the filling replenishing side of the loom is provided with a rear binder 21 which may be of any usual character or construction, and which is normally under the action of the binder finger 48, Fig. 3, mounted on the shaft 49 carried by the lay, as usual. When the shuttle-box is moved from its normal or weaving position, as indicated in Fig. 2 to its front position for replenishment of filling, as indicated in Fig. 3, the binder 21 leaves the binder finger 48; and in order at such times to still maintain the binder pressed firmly upon the shuttle in the box to thereby hold it rigidly for the action of the transfferer, the present invention provides means which is normally inactive during the weaving operation, but which, when the shuttle-box is moved forward of the lay, acts upon the binder to rigidly secure the shuttle in the shuttle-box. As one form of means to this end, the base portion 19 of the shuttle-box has pivoted thereto as at 50, Fig. 3, a shuttle clamp comprising an arm 51 adapted to engage the binder 21, as will hereinafter appear, and an arm 52 which, when the shuttle-box is in normal weaving position, rests upon a lug or shoulder 53 secured to the lay 6 but, which, when the shuttle-box is moved forward of the lay to position for filling replenishment, rides over the projection or shoulder 53 which thereby turns the clamp upon its pivotal mounting 50 and forces its upper arm against the binder. Obviously the upper arm might act directly against the shuttle, but it is preferable to have this action exerted through the binder. When the shuttle-box returns to its weaving position with respect to the lay, the shuttle clamp becomes inactive and the binder finger 48 assumes control of the binder 21.

A suitable source of supply for filled carriers is preferably provided in the form of a hopper or chute. In the present form of the invention, the chute comprises the base holding portion 54 and the tip holding por-

70

130

tion 55 for the filled carriers. These base and tip holding portions for the carriers may be appropriately supported in any suitable manner, but in the present form of the invention they are secured to an arm 56 mounted on the loom frame, substantially as indicated in Figs. 1, 2 and 3. The tip holding portion 55 of the chute is provided with a slot 57 through which may project the end portions 58 of the filling leading from the filling carriers, and a suitable arm 59 connected to the supporting arm 56 may be provided with a suitable stud 60, Figs. 3 and 5, to which the ends of the filling leading from the carriers may be secured.

It is desirable that the filling carriers be so controlled in the hopper that they may be presented in position for the transfer one at a time, and that such position shall not interfere with the movement of the picker spindle 13 during normal weaving operation. As a convenient form of means to these ends, the hopper in the present form of the invention has at the lower end of its base holding portion, a base rest 61, Fig. 2, for the lower one of the column of filling carriers when it is permitted to drop, as will hereinafter more fully appear. Likewise, the tip holding portion of the hopper is provided with a tip rest 62 on which the tip of the lower filling carrier in the hopper may rest when such filling carrier is permitted to drop to the lowest position. From the construction thus described as a preferred form of the lower portion of the hopper, it will be noted that said lower portion has a rearwardly extending opening through which a filling carrier may be forced into transferring position, as will now be described.

Mounted upon a suitable rock shaft 63, preferably secured to brackets 64, are the carrier positioning arms 65, the lower ends of which are provided with the pushers 66 for engaging and pushing the lowermost filling carrier into transferring position. The pushers on the arms 65 are preferably formed as indicated most clearly in Fig. 3 so as to provide an extended portion 67 which may contact with the body of the lowermost filling carrier between the base and tip engaging portions of the hopper.

In order to receive the filling carrier which is thus to be positioned by the positioning arms 65, the tip and base receiving portions of the hopper are provided with spring clips 68 and 69, respectively, substantially as indicated in Fig. 6. The holding portions of the spring clips 68 and 69 are provided with seats 70 and 71 respectively, so positioned with respect to the picker spindle 13 and shuttle-box at the filling replenishing side of the loom, that when the lay is at its front position, the filling carrier which is positioned for trans-

fer, will not be struck by the picker spindle 13, but will be held above the shuttle-box when the latter is given its additional forward movement upon call for filling replenishment.

Extending rearwardly from the shaft 63 is the arm 72, the rear end of which has a pin 73 which engages the slot 74 at the upper end of a link 75 which is connected at its lower end 76 to the transerrer arm 77 mounted to rock about the axis 78, Fig. 2, in effecting the transfer of a filling carrier to the shuttle, the construction being such that upon downward movement of the transerrer arm 77, the link 75 will be pulled downward until the upper end of its slot 74 contacts with the pin 73, whereupon the arm 72 acting through the shaft 63 will turn the positioning arms 65 into the position indicated in Fig. 3, to thereby withdraw the positioner 66 from beneath the column of filling carriers and permit the lowermost carrier to take position opposite the portion 67 of the positioner. As the transerrer arm 77 rises and assumes its initial position, the positioner 66 carried by the arms 65 will engage by its portion 67, the lowermost filling carrier in the hopper and force it rearwardly into the position between the end portions 70 and 71 of the spring clips 68, 69, respectively, substantially as indicated in Fig. 6. When the parts are in this position, the lowermost filling carrier in the hopper rests upon the substantially horizontal portion of the pusher 66 which thereby sustains the column of filling carriers in the hopper.

Projecting downward from the hub 79 of the transerrer arm 77 is the arm 80, to the lower end of which is pivotally mounted at 81, the dagger 82 having a notched end portion 83 for engagement with a bunter 84 carried by the shuttle-box carrying frame, the construction being such that during normal operation of the loom, the bunter 84 will not meet the dagger 83 and the loom will continue to weave without replenishing. When replenishment is called, however, and the shuttle-box is carried by its supporting frame into the position indicated in Fig. 3, as hereinbefore described, the bunter 84 will be moved an additional distance to the front, so that on forward movement of the lay, the bunter 84 will meet the dagger 83 and thereby cause the transerrer arm 77 to transfer a filling carrier from the spring clips 68 and 69 to the shuttle, which is then beneath the filling carrier to be transferred. The particular form of the transerrer arm 77 is not of the essence of the present invention, and it may be made with a base engaging portion 85 and a tip engaging portion 86, Fig. 6, for engaging respectively the base and the tip of the bobbin to effect its transfer.

It is desirable that the bobbin be directed

in its downward movement to the shuttle after it leaves the holding clips 68 and 69 of the hopper; and to this end the arm 87, Fig. 2, is fixedly mounted in position and 5 provided at its free end with a director 88 pivoted at 89 to said arm 87, a suitable spring being provided for normally holding the director 88 in its raised or normal position, as indicated in Fig. 2, the spring itself 10 not being shown as it is common in this type of loom, and well understood by those skilled in the art.

It is desirable that the action of the replenishing mechanism be suspended in case 15 the shuttle is not properly positioned in the box at the filling replenishing side of the loom; and to this end, the present invention provides a safety device, a practical and convenient form of which will now be described.

The safety device comprises a feeler arm 90, Figs. 2 and 3, pivotally mounted at 91 to a lug 92 extended downward from the bunter 82, to a point horizontally below the 25 pivotal connection between the dagger 82 and the arm 80, Fig. 3, a suitable stop 93 being provided to maintain the feeler arm 90 in operative position, substantially as indicated in Figs. 2 and 3.

The feeler arm 90 has its end portion extended toward the rear in proximity to the inner end of the shuttle-box at the filling replenishing side of the loom, and the feeler arm is of a length such that when the shuttle-box at the filling replenishing side of the loom is in weaving position, the end 94 of the feeler 90 will not be in the way of the shuttle movement or not cross the path of shuttle-movement when the lay is in its 40 front position. Upon call for filling replenishment, however, the shuttle-box is moved from its normal weaving position toward the front of the lay, substantially as indicated in Fig. 3, and when in such position, 45 the end 94 of the feeler arm 90 will, as the lay moves to its front position, pass the inner end of the shuttle provided it is properly positioned for replenishment in the shuttle-box; but if the shuttle should not be prop- 50 erly positioned, then the end 94 of the feeler arm 90 will contact with the shuttle as the lay beats up and the arm 90 will be moved frontwardly, thereby turning the dagger 82 about its pivotal connection with the arm 80 55 and depressing the end 83 of the dagger 82 out of the path of movement of the bunter 84, with the result that the bunter 84 fails to contact with and move the dagger 83 under the conditions stated, and the trans- 60 ferrer arm remains inactive.

In order to hold the dagger 82 and the feeler arm 90 in their normal positions as hereinbefore described, there is pivoted at 95 on the loom frame, a finger 96, the end 65 of which engages below the lug 92 of the

dagger 83, and under the impulse of the spring 97 acting upon the end 98 of said finger, holds the dagger and feeler arm in operative position, substantially as indicated in Fig. 2. A pin 99 serves to limit the upward movement of the finger 96 and define the normal operative position of the parts.

The particular means hereinbefore described constitute a good, practical form of the invention, the essentials of which, how- 75 ever, may be embodied in different particu-

lars of structure; and it will be evident that looms of the "overpick" type now in use may be readily adapted by slight changes, to embody the features of the present invention.

The toggle means for operating the shuttle-box carrying frame at the replenishing side of the loom has been found to be well adapted to its purpose, but obviously other means might be employed for thus 85

imparting to the said shuttle-box its additional movement toward the front of the loom to carry it into a position from below the picker spindle for the action of the replenishing mechanism.

It will be noted, 90 also, that the hopper for the filling carriers has a rearwardly extending opening through which the carrier next to be transferred is moved and placed in transferring position

between the spring arms. The transferring 95 position of the carrier next to be transferred is above but forward of the position of the shuttle in the box when the lay has reached its limit of forward movement during normal weaving operations; but when the shuttle-box is given its additional frontward

movement for the change of filling, the shuttle in the box becomes positioned substantially beneath the filling carrier next to be transferred.

What is claimed is:—

1. In a filling replenishing loom, the combination of the lay and shuttle-boxes, a hopper for containing filling carriers, means for transferring a filling carrier from said hopper to one of said shuttle-boxes, and means for moving the shuttle-box to one side of the lay when a carrier is to be transferred thereto.

2. In a filling replenishing loom, the combination of the lay and shuttle-boxes, means for moving the lay and shuttle-boxes toward and from the front of the loom, filling replenishing mechanism, means for giving one of the shuttle-boxes an additional movement 110 toward the front of the loom to position it for replenishment, and means acting through the top of the shuttle box when so positioned to effect replenishment.

3. In a filling replenishing loom, the combination of the lay and shuttle-boxes, picking mechanism including a part carried by the lay and normally above the top of the shuttle-boxes, filling replenishing mechanism, and means for moving one of the shut- 125 130

tle-boxes from under said part of the picking mechanism when the filling is to be changed to position it for replenishment.

4. In a filling replenishing loom, the combination of the lay and shuttle-boxes, picker spindles or guide rods above the shuttle-boxes, filling replenishing mechanism, and means for relatively moving the shuttle-box and picker spindle or guide rod at the replenishing side of the loom laterally of the lay out of their normal relation when the filling is to be changed to permit the filling carrier to be transferred to the shuttle.

5. In a filling replenishing loom, the combination of the lay and shuttle-boxes, picker spindles carried by the lay above the shuttle-boxes, filling replenishing mechanism, and means for moving the shuttle-box at the filling replenishing side of the loom from under the picker spindle when the filling is to be changed.

6. In a filling replenishing loom, the combination of the lay and shuttle-boxes, a source of filling carrier supply, a transerrer for transferring a filling carrier from said source of supply through the top of the shuttle-box, and means for moving said shuttle-box independently of the lay in the direction of lay movement when the filling is to be replenished to position the shuttle-box for the reception of a filling carrier.

7. In a filling replenishing loom, the combination of the lay, means for moving the lay backward and forward, shuttle-boxes movable with the lay, a source of filling carrier supply, a transerrer, means for moving the transerrer in a path in front of the lay when the latter is in front position, and means for moving one of the shuttle-boxes independently of the lay to place it in the path of the transerrer when the filling is to be replenished.

8. In a filling replenishing "overpick" loom, the combination of the lay, picker spindles carried by the lay, pickers movable relatively thereto for picking the shuttle, shuttle-boxes movable with the lay, filling replenishing mechanism, and means for moving one of said shuttle-boxes relatively to the lay to a position clear of the picker spindle that the replenishing mechanism may transfer a filling carrier to said shuttle-box when filling is to be replenished.

9. In a filling replenishing loom, the combination of the lay, shuttle-boxes movable therewith, filling replenishing mechanism, means for moving one of said shuttle-boxes independently of the lay to position it for the action of said mechanism when the filling is to be replenished, and means for preventing operation of the replenishing mechanism when the shuttle is not properly positioned in the box as the latter is moved independently of the lay.

10. In a filling replenishing loom, the

combination of filling replenishing mechanism, the lay, means for operating the lay, shuttle-boxes movable with the lay, means for moving one of the shuttle-boxes independently of the lay in the direction of lay movement when replenishment of filling is to be effected, and means operative by such independent movement of the shuttle-box to prevent operation of the replenishing mechanism when the shuttle is not properly positioned.

11. In an "overpick" loom, the combination of the lay and shuttle-boxes, a picker spindle carried by the lay adjacent each shuttle-box, a hopper for containing filling carriers, a transerrer, means for moving one of the shuttle-boxes toward the front of the loom beyond the front position of the lay when the filling is to be replenished, and means for operating the transerrer.

12. In an "overpick" loom, the combination of the lay and shuttle-boxes, a picker spindle carried by the lay adjacent each shuttle-box, a hopper for containing filling carriers, a transerrer, means for moving one of the shuttle-boxes toward the front of the loom beyond the front position of the lay when the filling is to be replenished, means for operating the transerrer, and means to prevent operation of the transerrer when the shuttle is not properly positioned in the box as it is moved beyond the front of the lay.

13. In an "overpick" loom, the combination of the lay, picker spindles mounted thereon, filling replenishing mechanism, shuttle-boxes movable with the lay, a frame supporting one of said shuttle-boxes for movement to one side of the lay, and means operative on call for replenishment for moving said frame and shuttle-box to position the latter at one side of the lay for the replenishing operation.

14. In a filling replenishing loom, the combination of the lay and shuttle-boxes, filling replenishing mechanism at one side of the loom, means for moving the shuttle-box at the replenishing side of the loom toward the front of the lay when filling is to be replenished, and a bunter movable with said shuttle-box into position beyond the front of the lay for operating the replenishing mechanism.

15. In a filling replenishing loom, the combination of the lay and shuttle-boxes, filling replenishing mechanism at one side of the loom, means for moving the shuttle-box at the replenishing side of the loom toward the front of the lay when filling is to be replenished, a bunter movable with said shuttle-box into position beyond the front of the lay for operating the replenishing mechanism, and a shuttle feeler to prevent operation of the replenishing mechanism if the shuttle is not properly positioned in the

shuttle-box when the latter is given its additional frontward movement.

16. In a filling replenishing loom, the combination of the lay and shuttle-boxes, filling replenishing mechanism, a shuttle feeler for preventing the operation of the replenishing mechanism if the shuttle is not properly boxed, means for sustaining and permitting the shuttle-feeler to remain in normal position, and means rendered effective on call for replenishment to cause the shuttle-feeler while still in normal position to determine if the shuttle is properly boxed.

17. In a filling replenishing loom, the combination of the lay and shuttle-boxes, filling replenishing mechanism, a shuttle feeler held in normal position out of the path of the shuttle during the normal weaving conditions, and means for advancing 20 the shuttle-box at the replenishing side of the loom on call for filling replenishment to position the shuttle-box for replenishment of filling and cause the feeler while in normal position to feel for the shuttle, and 25 means under control of the feeler to prevent operation of the replenishing mechanism when the shuttle is not properly boxed.

18. In a filling replenishing loom, the combination of a shuttle feeler normally held in position out of the path of the shuttle, a shuttle-box, means for moving the shuttle-box beyond its normal position toward the feeler when filling is to be replenished, filling replenishing mechanism, and 35 means controlled by the shuttle-feeler to prevent operation of said mechanism when the shuttle is not properly boxed.

19. A filling replenishing loom, comprising filling replenishing mechanism, the lay and shuttle-boxes, means for supporting one of said shuttle-boxes for movement toward the front of the loom in addition to the lay movement, a dagger and coöperating bunter, and means operated thereby as the 45 lay is moved after a call for filling replenishment to give said supporting means said additional movement to position the shuttle-box for filling replenishment.

20. A filling replenishing loom, comprising filling replenishing mechanism, the lay and shuttle-boxes, means for supporting one of said shuttle-boxes for movement toward the front of the loom in addition to the lay movement, a dagger and coöperating bunter, means operated thereby as the lay is moved after a call for filling replenishment to give said supporting means said additional movement to position the shuttle-box 55 for filling replenishment, and means to prevent operation of the replenishing mechanism when upon such additional movement of said shuttle-box the shuttle is not properly positioned.

21. In a loom of the character described,

the combination of the lay, filling replenishing mechanism, shuttle-boxes movable with the lay, a frame carrying one of said shuttle-boxes and movable with the lay, and means operative upon call for filling replenishment for moving said frame toward one side of the lay to position the said shuttle-box for the replenishing operation.

22. In a loom of the character described, the combination of the lay and shuttle-boxes movable therewith, filling replenishing mechanism, one of said shuttle-boxes being supported for movement to one side of the lay in addition to the lay movement, means for imparting such additional movement to the shuttle-box on call for filling replenishment, and a clamp for holding the shuttle in the shuttle-box when the latter is given said additional movement and during filling replenishment.

23. In a filling replenishing loom, the combination of the lay, a shuttle-box including a binder, a binder finger for acting on the binder, filling replenishing mechanism, means for moving the shuttle-box relative to the lay and binder finger when the filling is to be changed, and a clamp for holding the shuttle in the shuttle-box during the replenishing operation when the shuttle-box is moved away from the binder finger.

24. In a loom of the character described, the combination of the lay and shuttle-boxes movable therewith, filling replenishing mechanism, one of said shuttle-boxes being supported for movement to one side of the lay in addition to the lay movement, means for imparting such additional movement to the shuttle-box on call for filling replenishment, and a normally inoperative clamp for holding the shuttle in the shuttle-box when the latter is given said additional movement and during filling replenishment.

25. In an "overpick" filling replenishing loom, a hopper for containing a supply of filling carriers, the lay and shuttle-boxes, means for supporting the hopper with the carrier next to be transferred above and in front of the forward limit of lay movement, means operative when filling is to be replenished for moving one of the shuttle-boxes frontward of the lay beneath the carrier next to be transferred, and means for transferring the filling carrier to said shuttle-box when in said front position.

26. In a filling replenishing loom, the combination of the lay and shuttle-boxes including the shuttle binders, filling replenishing mechanism and means operative only on call for replenishment for clamping the shuttle in the box adjacent the filling replenishing mechanism, during the replenishing operation.

27. In a filling replenishing loom, the combination of a hopper, a transferrer,

means for operating the transfer, a filling carrier positioning device having a portion extending transversely of the hopper to support the filling carriers in the hopper and a portion at an angle thereto to engage and move a filling carrier from said hopper to a position for transfer, means for operating the positioner, and spring clips for leaning against the ends of and supporting the carrier in transferring position.

28. In a filling replenishing loom, the combination of a filling carrier supply hopper, a transfer for transferring a filling carrier from said hopper to the shuttle, a filling carrier positioner having a portion adapted to extend transversely of and support the filling carriers in the hopper and an angular portion to engage a filling carrier and move it to transferring position, and means for operating said positioner.

29. In a filling replenishing loom, the combination of a filling carrier supply hopper, a transfer for transferring a filling carrier from said hopper to the shuttle, a filling carrier positioner comprising pivotally mounted arms having an angular member connected thereto, one portion of said

angular member being adapted to support the filling carriers in the hopper and another portion to engage and move the lowest filling carrier to transferring position, and means for operating said arms and angular member.

30. In a filling replenishing loom, the combination of filling replenishing mechanism, the lay and shuttle-boxes, means for supporting one of said shuttle-boxes for movement to one side of the lay to position the shuttle-box for filling replenishment, means for holding said shuttle-box in line with the race, and means for moving the shuttle box in opposition to said holding means when the filling is to be changed and for releasing the shuttle-box to the control of said holding means when the filling has been changed.

In testimony whereof, I have signed my name to this specification, in the presence of two subscribing witnesses.

WILLIAM H. BAKER.
